UNITED STATES PATENT OFFICE.

WASHINGTON H. KILBOURN, OF GREENFIELD, MASSACHUSETTS.

AUTOMATIC CARRIAGE-RETURN FOR TYPE-WRITING MACHINES.

1,095,282.

Specification of Letters Patent.

Patented May 5, 1914.

Application filed April 9, 1913. Serial No. 759,941.

To all whom it may concern:

Be it known that I, WASHINGTON H. KILBOURN, a citizen of the United States, residing at Greenfield, in the county of Franklin 5 and State of Massachusetts, have invented certain new and useful Improvements in Automatic Carriage-Returns for Type-Writing Machines, of which the following is a specification.

10 This invention relates to typewriting machines, and has particular reference to the carriage which supports the paper platen.

The principal object of the invention is to provide means for automatically returning 15 the carriage to the right when a new line of writing is to be commenced.

A further object is to effect the actuation of the platen to feed the paper, simultaneously with the actuation which results in the 20 automatic return of the carriage.

A further object is to provide means whereby the spring which is ordinarily employed to effect the travel of the carriage to the left may be dispensed with, the step by 25 step feed of the carriage toward the left when writing or spacing, being effected by the manual operation of the finger levers or keys, or the space bar.

To this end the invention consists in the 30 improvements which I shall now proceed to describe and claim.

Of the accompanying drawings,—Figure 1 is a side elevation, partly broken away or in section, illustrating a well known form of 35 typewriting machine having my improvements applied thereto. Fig. 2 represents a section on line 2—2 of Fig. 1. Fig. 3 represents a section on line 3—3 of Fig. 1. Fig. 4 is a plan view.

40 In all of the figures, many of the parts of the typewriting machine itself are omitted, to avoid confusion.

Similar reference characters indicate similar parts in all of the figures.

45 The frame of the typewriting-machine as a whole is indicated at 12, said frame having the usual rails and mechanism for supporting the carriage 13, which latter supports the platen-roll 14. The platen roll has the usual 50 ratchet 15, and escapement pawl 16 carried by a lever 17 pivoted at 18, and having a handle 19 for effecting the operation of the platen-roll to feed the paper. One of the usual type-levers of the machine is indicated 55 at 20, said lever being connected by a link 21 with the finger lever or key 22. The space

key or space bar 23 is carried by the usual arms or levers 24, said arms or levers and also the finger levers or keys being pivoted on the usual rod 25. Extending transversely of the typewriting-machine, under the levers 22, 24, is the cross-bar 26, connected by links 27 (Fig. 3) with an upper bar 28 rigidly connected to one arm of an elbow lever 29, 30, of the kind which is usually employed for controlling the step by step feed of the carriage under the influence of the usual spring, which spring, however, with my present improvements, may be omitted, as hereinafter described.

A spring 31 is connected to the elbow lever 29, 30, to exert a tension on said lever to swing it in the direction opposite that of the arrow in Fig. 1, and in the direction to raise the cross-bar 26.

I will now proceed to the specific description of my improvements. A vertical guide-rod 32 is rigidly secured, as by having its lower end stepped firmly in a rear portion of the base of the frame, a weight frame 33 being mounted to slide vertically on said guide-rod. In the embodiment of the invention illustrated, the weight frame includes a piece of sheet metal, but I do not limit myself to the use of sheet material. The weight 38 has inclined edge rails 34, 35, (Fig. 3), the lower end of the former terminating in a hook-shaped end 36, and the upper end of the rail 35 terminating in a hook-shaped end 37. Guide wheels 38 engaging the rod 32 are carried by brackets 29 secured to the weight. Said weight may have a pocket 40 for the reception of any suitable material to variably increase the weight of the vertically movable rails 34, 35. The weight as a whole, 45 has secured thereto a vertical ratchet rack 41, pawl mechanism as hereinafter described, being employed to engage said ratchet rack to lift the weight and its edge rails step by step whenever a finger key, or the space-bar is 50 actuated.

The carriage 13 has brackets 42 carrying wheels 43, 44, which respectively engage the inclined rails 34, 35. It will now be understood that vertical movements of the weight frame, between the full and dotted line position shown in Fig. 3, will cause the carriage to travel on its rails whenever it is permitted to do so, or is actuated by the pawl mechanism which I shall now describe.

55 Referring particularly to Fig. 1, it will be seen that a link 45 connects the upper arm 30

of the elbow lever with a similar elbow lever 46 pivotally connected to the rear part of the upper portion of the frame of the typewriting machine. Said elbow lever 46 is pivoted at 47 to a substantially vertical lever 48 having a pawl 49 at its upper end, said pawl engaging the ratchet rack 41 so that whenever the elbow lever 29, 30, is actuated in the direction of the arrow shown in Fig. 1, either by the manipulation of a finger key lever, or by the space-bar, the motion will be transmitted through the link 45 and small elbow lever 46 to lower the lever 48 a distance slightly in excess of the length of one tooth of the rack 41, so that the pawl 49 will engage the next tooth below. Upon the release of the finger-key-lever, or space-bar, the spring 31 causes these parts to return to normal position; the pawl 49 lifting the weight frame. The upward movement of the weight frame causes the inclined rail 34 to shift the carriage to the left, and obviously this is done step by step, and may be repeated to an extent to cause the complete travel of the carriage to the left. If the usual spring that is employed for feeding the carriage to the left is retained, its tension should be very light.

A detent pawl 50 engaging the ratchet rack just under the lifting pawl 49, is carried by the arm 51, pivotally supported at 52, a lower angular portion of said arm 51 being engaged by the spring 53 (Figs. 1 and 4) to yieldingly hold the detent pawl in position, to retain the ratchet rack and the weight at the elevation to which it has been raised by the operation of the pawl 49. The arm 51 has a lateral pin 54 extending across the rear edge of the upper end of the lever 48, for a purpose hereinafter described.

The lower end of the lever 48 is engaged by a loop or arm 55, extending forwardly from an upright 56 carried by a slide rod 57 mounted in the base of the frame of the machine, said rod having at its front end a finger push 58 (Fig. 4). A spring 59 is connected to the slide rod 57 to hold it in its normal forward position. Whenever it is desired to effect the automatic return of the carriage to the right, the operator simply pushes the finger piece 58 so that the loop 55 will oscillate the lever 48 to release the lift or pawl 49 from the ratchet rack. Movement of the ratchet pawl in the direction thus described causes it to engage the pin 54 so as to release the detent pawl 50. This instantly permits the weight to descend by gravity, so that its righthand edge rail 35, by riding downwardly over the wheel 44 of the carriage, will impel the carriage to the right until the hook 37 engages the wheel 44, and prevents further movement. The machine is then ready to begin a new line, provided the platen is shifted. I have provided means whereby when the operator releases the

weight in the manner just described, the rotation of the platen roll to feed the paper may be simultaneously effected. To do this I employ a flat bar 60 normally occupying the position shown in Fig. 1, behind the lower end of the handle 19. Said bar is carried by two arms 61 (Figs. 1 and 2) pivoted to the base of the frame at 62. A slide plate 63 has arms 64 provided with pins engaging slots 65 in the lower ends of the arms 61. A center rod 66 is connected to the slide plate 63 and projects through the front rail of the base of the frame of the machine, and has a finger push 67 in close proximity to the finger push 58, as shown in Fig. 4. A spring 68 holds the parts just described normally in the position shown in Fig. 1.

While the operator may at any time actuate the finger push 58 alone to release the weight, by simply pressing the thumb or finger against both of the push pieces 58, 67, the flat bar 60 will be caused to actuate the lever 17 by engaging the lower end of the handle 19, regardless of the lateral position of the latter. Of course, the push piece 67 may be alone actuated whenever it is desired to do more or less line spacing, or feed the paper. It will now be understood that I have provided means whereby during the operation of the type levers, or the space key or bar, energy is stored up by the lifting of the weight, said energy being then capable of being utilized by releasing the weight which then acts as an impeller, to automatically urge the carriage toward the right, or to position to begin a new line, and of course, it will be understood that whenever desired, the energy stored up in the weight may be manually released by operation of said rod 57, and as has been explained, the gradual or step by step lifting of the weight which stores the energy just described, may be utilized to feed the carriage step by step, without the employment of any spring for shifting the carriage to the left.

It is to be understood that while the drawings illustrate my improvements in connection with a writing machine of not the most recent type, I do not limit myself thereto, as the improvements may be employed in connection with other and later types of "visible writing" machines.

I claim:

1. The combination with a typewriting machine having a carriage provided with a rearward extension, of a vertically movable impeller having an inclined rail engaging said extension for returning the carriage to position to begin a new line, and connections whereby the manual operation of the type-levers when writing will raise the impeller step by step.

2. The combination with a typewriting machine having a carriage provided with rearward extensions, of an impeller mov-

able in a path at an angle to the plane of travel of the carriage, said impeller having inclined rails engaging said extensions, and connections whereby the manual operation 5 of the type-levers when writing will raise the impeller step by step.

3. The combination with a typewriting-machine having a carriage provided with rearward extensions, of an impeller movable 10 in a path at an angle to the plane of travel of the carriage, said impeller having inclined rails engaging said extensions, connections whereby the manual operations of the type-levers when writing will raise the 15 impeller step by step, means for manually releasing the impeller at any point of its elevation, and connections whereby the descent of the impeller will return the carriage to begin a new line.

20 4. The combination with a typewriting-machine having a carriage provided with rearward extensions, of an impeller movable in a path at an angle to the plane of travel of the carriage, said impeller having inclined rails engaging said extensions, connections whereby the manual operation of 25 the type-levers when writing will raise the impeller step by step, and means for manually releasing the impeller at any point of its elevation and simultaneously line-spacing 30 the paper, whereby the descent of the impeller will return the carriage to position to begin a new line.

5. The combination with a typewriting-machine and the carriage thereof, of means 35 for returning the carriage to position to begin a new line, said means comprising a vertically movable impeller having an inclined rail, and a wheel connected to the carriage and engaged by the inclined rail. 40

6. The combination with a typewriting-machine and the carriage thereof, of an impeller having two inclined edge rails, wheels connected to the carriage of the machine and engaging said rails whereby the carriage 45 will be shifted in either direction by the engagement of a rail with one of said wheels, and means for raising said impeller step by step when the finger keys or the space-bar of the machine are operated. 50

7. The combination with a typewriting-machine and the carriage thereof, said carriage being provided with wheels, of a vertically movable impeller having edge rails engaging said wheels, a ratchet rack connected to said impeller, a lifting pawl engaging said ratchet, and connections for actuating the lifting pawl by the finger keys of the machine. 55

In testimony whereof I have affixed my 60 signature, in presence of two witnesses.
